UNITED STATES PATENT OFFICE.

EDWIN N. GREENWOOD, OF CHICAGO, ILLINOIS, ASSIGNOR TO NATIONAL METAL BUNG COMPANY, OF CHICAGO, ILLINOIS.

BUNG.

SPECIFICATION forming part of Letters Patent No. 764,120, dated July 5, 1904.

Application filed June 20, 1903. Serial No. 162,389. (No model.)

To all whom it may concern:

Be it known that I, EDWIN N. GREENWOOD, a citizen of the United States, residing at Chicago, in the county of Cook and State of Illinois, have invented a new and useful Improvement 5 in Bungs, of which the following is a specification.

The object of my invention is to provide a construction of metal bung which shall support plant bungs cast from metal.

The cast-metal bung in all of the various constructions in which it is provided is objectionable by reason of its weight, its rigidity, and the cost of producing it. When such a bung is driven into the bung-hole of a cask or into the bushing with which the bung-hole is equipped, the bung becomes tightly wedged therein, and because of its rigidity the matter of withdrawing it involves great difficulty, often causing either fracture of the bung or 20 injury to the cask.

My improved construction of metal bung renders it comparatively cheap to manufacture, light in weight, and so yielding that while it holds its position when driven into place as securely as the cast-metal article it may be withdrawn easily without danger of injury to itself or to the cask.

To produce my improved article, I form it in two parts, one contained within the other and permanently secured therein.

Referring to the accompanying drawings, Figure 1 is a plan view of a sheet-metal disk forming a blank to be stamped into cup shape and afford the outer part of the bung; Fig. 2, a similar view of a like disk, but of smaller diameter and provided with a central opening to be stamped into cup shape and afford the inner part of the bung; Fig. 3, a perspective view of the cup formed from the blank shown in Fig. 1; Fig. 4, a similar view of the cup formed from the blank shown in Fig. 2; Fig. 5, a similar view of the complete bung, and

Fig. 6 an enlarged section taken at the line 6 on Fig. 5 and viewed in the direction of the 45 arrow.

From a disk *a*, of sheet-steel, I form by stamping with a suitable die the cup *A*, (represented in Fig. 3,) and from a disk *a'*, of the same material, somewhat smaller in diameter 5° than the disk *a* and containing a central opening *a*², I form in a similar manner the cup *A'*, (represented in Fig. 4.) The smaller cup is introduced in inverted position into the cup *A* to bear at its open end against the base of the 55 outer cup, whereby the open end of the latter, owing to its greater length, projects beyond the perforate closed end of the cup sufficiently to afford a flange *b*, formed by bending the 60 projecting portion of the cup *A* over the adjacent end of the inner cup, to securely and permanently unite the two parts and produce the bung *B*. The opening *a*² admits a bung-puller.

The bung may be finished to ornament it by 65 coating it with tin or other suitable material, which fills the seam between the flange and inner cup and that between the inner edge of the cup *A'* and the base of the outer cup. Both cups are shown slightly rounded about their 70 outer edges as a result of the stamping operation of forming each.

The form of the parts may be changed and the construction may be variously modified in matters of detail without departure from my 75 invention, which is therefore not intended to be limited to the exact construction herein shown and described.

What I claim as new, and desire to secure by Letters Patent, is—

1. A bung adapted to be driven in the bung-hole of a barrel, consisting of an inner inverted rigid metal cup-shaped member, and an outer rigid metal cup-shaped member into which the inner member closely fits, said outer 85 member having a closed lower end and a con-

tinuous inwardly-extending rigid flange at its upper end overlapping and permanently confining the inner inverted member.

2. A bung adapted to be driven in the bung-hole of a barrel, consisting of an inner inverted rigid metal cup-shaped member having a puller-opening, and an outer rigid metal cup-shaped member into which the inner member closely fits, said outer member having a

closed lower end and a continuous inwardly-extending rigid flange at its upper end overlapping and permanently confining the inner inverted member.

EDWIN N. GREENWOOD.

In presence of—

WALTER N. WINBERG,
A. C. KITTELESON.
